Geneva, Switzerland, a corporation of Switzerland

Application April 14, 1949, Serial No. 87,460
In Switzerland April 16, 1948

9 Claims. (Cl. 321—50)

1

Hitherto the construction of converters has been based on the following principles.

1. The use of solid contacts which are periodically pressed against each other and removed from each other. These converters with solid contacts present several drawbacks, viz.:

(a) Synchronism must be very accurate to avoid the contacts of two adjacent phases from being opened simultaneously;

(b) Special means (inductances) are required for effecting commutation in order to avoid return currents and the formation of arcs;

(c) The electrodes wear out quickly unless important and relatively costly inductance coils are used as commutation means.

2. The use of a mercury vapor arc in a vacuum. In this case the voltage drop in the arc is practically constant and equal to approximately 20 volts. This means that when operating at low voltages the losses are relatively high.

3. The use of a jet of mercury movable in respect to a solid electrode with which it comes in contact periodically. In this case an appreciable amount of power is consumed by the circulation of the mercury for producing the jet.

The present invention aims at avoiding these drawbacks presented by the commutators already known and at providing a converter capable to operate under the best conditions both for low voltages and power and for high voltages and power.

The present invention provides a converter of the type comprising at least one contact which opens and closes synchronously with the frequency of the network, characterized in that it comprises at least one container containing mercury and at least one solid electrode, which container rotates planetarily on an axis which is movable round a fixed axis in order to communicate to the mercury a relative motion with regard to the said solid electrode, and in that the mercury constitutes the cathode for the whole duration of each passage of the current, the commutation taking place on the opening of the circuit in the arc formed between the said cathode and the opposite electrode.

It is evident that with such an arrangement the drawbacks of converters with solid electrodes and those relating to mercury vapor converters may be avoided. Moreover, the power required to communicate to the mercury a relative motion with regard to the solid electrode is negligible, with the result that the drawback mentioned above in connection with mercury jet converters is also avoided.

2

In the converter according to the invention, the commutation takes place in the arc, which obviates, without any special appliance, the drawbacks mentioned in connection with solid contact converters. Furthermore, it will be noticed that the negative characteristic of the arc (increasing resistance as the voltage is reduced) ensures automatic extinction of the arc used for commutation.

10 The accompanying drawing illustrates by way of example two embodiments of the converter according to the invention.

Fig. 1 is an axial longitudinal section of the first embodiment.

15 Fig. 2 is a cross-section along the line II—II in Fig. 1;

Fig. 3 is a cross-section along the line III—III in Fig. 1;

20 Fig. 4 is a connection diagram of this first embodiment;

Fig. 5 is a view of a detail of a variant;

Fig. 6 is a cross-section of the second embodiment;

25 Figs. 7 and 8 are views of the details of this second embodiment.

The converter illustrated comprises a cylindrical metallic envelope 1 to whose ends are fixed by means of bolts two bottoms 2 and 3. A shaft 4 which turns in the direction indicated by the arrow 5 passes axially through the center of the bottom 3. The opposite bottom 2 is axially crossed by a shaft 6 arranged precisely in line with the shaft 4. The latter is affixed with a disk 7 in which two ball bearings 8 and 9 are fitted at the same distance from the geometric axis of the shaft 4 and in diametrically opposite position. Through the ball bearings 8 and 9 pass two tubes 10 and 11, respectively, parallel to the shaft 4 round whose axis they rotate together with the disk 7. In order to give the whole arrangement the required rigidity, there is a second disk 12 parallel to the first disk 7 and carrying two ball bearings 13 and 14 through which the tubes 10 and 11, respectively, also pass.

45 The tube 10 is welded to a small disk 15 to which is attached by means of the screws 16 a cog 17 which is always in mesh with a crown wheel 18 with internal gearing. The tube 11 is welded to a small disk 19 to which is attached in like manner by means of the screws 20 a cog 21 which is always in mesh with a crown wheel 22 with interior gearing. The two crown wheels 18 and 22 have the same size and are placed side by side. Their external spiral gearings 23 and 24, respectively, engage with the screws 25 and

26, respectively, which screws are arranged in an embossment 27 of the envelope 1 in such a way that they rotate without any axial displacement. At one end of these screws, as indicated in 29 for the screw 26, there is a square head by means of which the screws can be turned round their own axes with the help of an adjusting spanner. By turning the screws 25 and 26 the crown wheels 18 and 22 can be made to rotate round the axis of the converter.

The shaft 6 is firmly attached to a disk 29 parallel to and of the same size as the disk 7. Inside the disk 29 there are two ball bearings 30 and 31 through which pass two tubes 32 and 33, respectively, placed exactly in line with the tubes 10 and 11, respectively, mentioned above. The disks 7 and 29 are rigidly connected by means of two rods 34 and 35 parallel to the axis of the converter and fixed at their ends to the two afore-mentioned disks. It is obvious from the drawing that the rods 34 and 35 are arranged in a radial plane with respect to the axis of the converter, which axis is perpendicular to the radial plane which contains the axis of the tubes 10 and 32 on one side and 11 and 33 on the other. The rods 34 and 35 ensure of course the rigid connection not only between the disks 7 and 29, but also between them and the disk 12.

The tube 10 is also welded to a small disk 36 similar to the disk 15, to which is attached by means of the screws 37 a part 38 made of insulating material whose purpose will be indicated later. In like manner, the tube 11 is welded to a small metallic disk 39 similar to the disk 19, to which is attached by means of screws 40 a part 41 made of insulating material and identical with the part 38 just mentioned.

The tube 32, coaxial with the tube 10, is also welded to a small metallic disk 42 to which is attached by means of the screws 43 a part 44 made of insulating material which is placed exactly opposite the part 38 but a certain distance away. Finally, the tube 33, coaxial with the tube 11, is welded to a small disk 45 to which is attached by means of the screws 46 a part 47 made of insulating material which is exactly opposite the part 41 but a certain distance away.

Inside the cylindrical envelope 1 there is a cylindrical lining 48 made of insulating material. Inside the insulating lining 48 there are four identical metal rings 49, 50, 51 and 52 placed a certain distance apart and insulated from each other by the insulating rings 53, 54, and 55, respectively. A similar insulating ring 56 is placed between the metal ring 52 and the adjacent crown wheel 22. Each of the conducting rings 49, 50, 51 and 52 is attached to one of the electric terminals 57, 58, 59 and 60, respectively, which pass through the envelope 1 and the insulating lining 48 and are screwed into their respective rings. An insulating sleeve 61 surrounds each of the said terminals in order to insulate it from the envelope 1.

The inner cylindrical surface of each of the rings 49, 50, 51 and 52 constitutes a roller track for a roller that will now be described. The roller which rolls inside the ring 52 is shown at 62 and is arranged so as to be constantly coaxial with the tubes 10 and 32. It is angularly firmly attached to the insulating part 38 by means of three pins 64 whose free ends engage in cavities in the said part 38. This end of each pin 64 is surrounded by a sleeve 65 made of an elastic material such as rubber designed to permit a slight angular displacement of the pins 64 relatively to

the axis of the tube 10 in order to ensure that the roller 62 is always pressed firmly against the track arranged in the ring 52. The roller 62 is keyed on to a small shaft 66 coaxial with the tubes 10 and 32.

The roller which rolls inside the ring 51 is shown at 67 and is angularly firmly attached to the insulating part 41 by means of three pins 68 whose free ends engage in cavities in the said part 41. 10 These ends are fitted with a packing 69 made of an elastic material such as rubber in order to allow the pins 68, if necessary, a slight inclination in respect to the axis of the tube 11 in order to ensure that the roller 67 is always pressed firmly against the track arranged in the ring 51. This roller 67 is keyed on to a small shaft 70 coaxial with the tubes 11 and 33.

The roller which rolls inside the ring 50 is formed by an annular projection 71 on a metal drum 72 that constitutes the side wall of a container 73 which holds a certain amount of mercury 74. The said container 73 is closed at each end by the metal bottoms 75 and 76. Through the bottom 76 passes the small shaft 66 whose free end is prolonged inside the container 73. Two rings 77 and 78 made of insulating material ensure a tight joint between the shaft 66 and the bottom 76 and at the same time a rigid connection between the container 73 and the shaft 66. The connection between the bottom 75 of the container 73 and the insulating part 44 is similar to that between the roller 62 and the insulating part 38. Three pins 79 are firmly fixed to the said bottom 75 and their free ends engage in cavities in the insulating part 44, a packing 80 made of an elastic material such as rubber being fitted round the said end of each pin to allow the said pins, if necessary, a slight inclination in respect to the axis of the tube 32 in order to ensure that the roller 71 is always firmly pressed against the track arranged in the ring 50.

The bottom 75 is also traversed axially by a small tube 81 closed by a screw 82 which functions as a plug. This small tube 81 is used for introducing the mercury 74 into the container 73.

The small shaft 70 supports a container 83 identical with the container 73. The roller that rolls inside the ring 49 is constituted by an annular projection 84 on a cylindrical piece 85 that forms the side wall of the container 83. The said container 83 is closed at one of its ends by a bottom 86 identical with the bottom 76 and at the other end by a bottom 87 identical with the bottom 75. Insulating rings 88 and 89 identical with the rings 77 and 78 ensure a tight joint between the shaft 70 and the bottom 86 and a rigid connection between the said shaft and the said bottom. Mercury 90 is placed in the container 83. A small tube 91 that passes axially through the bottom 87 is used to introduce the mercury. This tube is closed by a screw 92 which functions as a plug.

The bottom 87 of the container 83 is attached to the insulating part 47 by means of three pins 93 firmly fixed to the said bottom and whose free ends engage in cavities in the said part 47. In this case also the said end of each pin is surrounded by a packing 94 made of elastic material such as rubber to allow the pins 93, if necessary, a slight inclination in respect to the axis of the tube 33 in order to ensure that the roller 84 is always firmly pressed against the track arranged in the ring 49.

On the free end of the shaft 66, which, as we have seen, is prolonged inside the container 73, there is a number of metal fins 95 which extend

radially to the proximity of the cylindrical wall 72. These fins which have all the same profile, illustrated in Fig. 2, viz. a segment of a circle of small aperture, are keyed on to the shaft 66. The number of the fins depends on the intensity of the current to be allowed to pass through the converter. In fact, as will be seen later, these fins constitute one of the two electrodes (the other being constituted by the mercury 74) between which the opening and closing of the circuit is effected.

In like manner the fins 96, identical with the fins 95, are keyed on to the shaft 70 and constitute one of the two electrodes (the other being constituted by the mercury 90) between which the opening and closing of the circuit is effected.

The converter described above operates in the following manner:

When the shaft 4 rotates in the direction of the arrow 5 the axis of the containers 73 and 83 are driven with it at the same angular speed. Consequently, the axes of the said containers revolve round the fixed axis of the converter. Moreover, the rotation of the shaft 4 causes the cogs 17 and 21 to revolve on the interior gearing of the crown wheels 18 and 22, respectively. The diameter of the said cogs is exactly half that of the gearing of the said crown wheels. The diameter of the four cylindrical tracks in the rings 49, 50, 51 and 52 is equal to that of the gearings of the crown wheels 18 and 22. Furthermore, the diameter of the four rollers 62, 67, 71 and 84 is equal to that of the cogs 17 and 21. Consequently, the rollers 62, 67, 71 and 84 roll without sliding on their respective tracks causing the containers 73 and 83 to rotate round their own axes while the said axes revolve round the main axis of the converter.

The centrifugal force due to the motion of the containers round the fixed axis of the converter drives the mercury as far as possible from the said axis so that it takes up the position indicated in Fig. 2, where in each of the containers 73 and 83 its free surface assumes the shape of part of a cylinder whose axis is the axis of the converter. The rotation of the containers round their own axes causes the shafts 66 and 70 to rotate round their own axes in the direction contrary to that of the shaft 4.

In Fig. 2 the arrow 97 indicates the direction in which the disk 29 rotates, i. e. the shaft 4, and the arrows 98 and 99 indicate the directions in which rotate the shafts 66 and 70 and their fins 95 and 96, respectively. It follows that the conducting fins 95 and 96 are introduced periodically into the mercury and periodically withdrawn from it. The velocity of rotation of the shaft 4 is selected in such a way in relation to the frequency of the network that the formation of the contact between the fins and the mercury and the breaking of the said contact are synchronized with that frequency. If, for instance, the converter is to be employed as a rectifier in a monophase circuit, the connections are arranged as indicated schematically in Fig. 4. The secondary winding 100 of the feed transformer has a median pole 101. One end of the secondary winding 100 is connected with the terminal 57 and the other end with the terminal 58. The terminals 59 and 60 are connected with a common point 102. The circuit 103 of the current rectified by the converter is arranged between the points 101 and 102. It could be seen that during one semi-period one of the containers 73, 83 functions as rectifier while the other is idle, and during the other

semi-period the reverse is true. Therefore the current enters at the terminal 58 and passes successively through the ring 50, the roller 71 and the metal wall 72 of the container 73 till it reaches the mercury 74. At the instant under consideration the metal fins 95 dip into the mercury. Consequently the current passes successively from the mercury through the said fins, the shaft 66, the roller 62 and the ring 52 to the output terminal 60. During that time no current circulates between the terminals 57 and 59 since the fins 96 are out of contact with the mercury 90.

The arrangement is provided in such a way that the mercury forms the cathode for the whole time the current passes through one of the containers. Under those conditions the commutation takes place, on the opening of the circuit between the respective fins and the mercury, in the arc that is formed between the mercury cathode and the opposite electrode, i. e. the solid metal fins.

In the example described above the solid electrode constituted by the fins 95, respectively 96, acts as anode during the whole passage of the current. In the variant according to Fig. 5 the said solid electrode acts as anode for the major part of the time the current passes through the respective container. In this case, in each of the fins, for instance 95, at the part that leaves the mercury 74 on the opening of the circuit, there is a funnel-shaped cavity 104 open at each end. This cavity is designed in such a way that it is filled with mercury when it dips into the mass of mercury 74 and that the arc which effects the commutation is formed between the drop of mercury 105 that appears at the small end of the cavity 104 and the surface of the mercury 74. Simultaneously with the commutation and the extinction of the arc the small quantity of mercury contained in the cavity 104 escapes therefrom under the action of the centrifugal force. In this variant the arc is formed during the brief instant of commutation between the mercury 74 that acts as cathode and the drop of mercury 105 temporarily lodged in the fin 95. Consequently, during that brief instant the said drop of mercury acts as anode.

It will be noticed that in the embodiment described above the current is fed to the electrodes without using sliding contacts or flexible conductors. In this way wearing out of the leading contacts and breaking through fatigue of the flexible conductors employed in many of the known devices are avoided. Here, as already seen, the current is fed by means of rollers which roll practically without any slip on a fixed metal track, so that practically no wear occurs. Good contact between the said rollers and their respective tracks is ensured by the fact that the rollers are pressed firmly against the tracks by the centrifugal force.

It should likewise be noted that the instant of commutation in each of the containers can be adjusted at will by mechanical means even while the converter is in operation. In fact, the adjusting screws 25 and 26 enable the angular position of each container in respect to its own axis to be adjusted without any displacement of this axis around the main axis of the converter. Finally, it will be noted that as a result of the movement of the containers round the fixed axis the mercury is subjected to a centrifugal force which is amply sufficient to stabilize the surface of the said mercury at the point where commutation takes place, and to obviate any parasite

oscillations that might disturb the precision (in respect of time) of the said commutation.

The second embodiment illustrated in Figs. 6-8, comprises a casing 106 in which rotate two shafts 107 and 108 arranged exactly in line with each other and firmly attached to a rectangular frame 109. The shaft 107 is attached to a driving pulley 110 which communicates a rotatory movement to the frame 109. Three contact rings 111, 112 and 113 are keyed or shrunk on to the shaft 108 and are electrically insulated from each other. With each of these rings cooperate one of the brushes 114, 115 and 116, respectively, carried by the brush-holders 117, 118 and 119, respectively, which are supported by an arm 120 firmly attached to the casing 106.

Through the center of the frame 109 passes a shaft 121 perpendicular to the common axis of the shafts 107 and 108. The shaft 121 carries a conical cog 122 which meshes with the fixed conical geared crown wheel 126 arranged inside the casing 106. The shaft 121 also carries three rings 123, 124 and 125 electrically insulated from each other. With each of these rings cooperates one of the pairs of brushes 127, 128 and 129, respectively, carried by the pairs of brush-holders 130, 131 and 132, respectively, which are supported in turn by two arms 133 and 134 attached to the frame 109 and extending parallel to the shaft 121. Finally, on that part of the said shaft 121 which lies inside the frame 109 is keyed or shrunk a wheel 135 on whose rim is arranged a tore-shaped container 136. The part of the container 136 shown in cross-section in Fig. 6 is reproduced on a larger scale in Fig. 7, where 137 is the disk of the wheel 135 and 138 its rim. Around this rim are fitted two rings 139 and 140 made of insulating material. These rings are kept apart by an insulating ring 141 which is disposed between them at their portion which is further away from the shaft 121. A metal ring 142 having a radial flange 143 embraces the rings 139, 140 and 141. An annular plate 144 screwed to the side of the rim 138 and to the side of the ring 142 opposite the flange 143 keeps the unit formed by the rings 139, 140, 141 and 142 in place on the rim 138. The rings 139, 140, 141 and 142, in conjunction with the rim 138, form an annular chamber 145 of rectangular cross-section in which there is a certain amount of mercury (not shown in the drawing).

In the sides of the insulating rings 139 and 140 that face each other annular cavities 146 and 147, respectively, are cut. These two cavities are exactly opposite each other. In the cavity 146 is arranged a metal ring 148, shown in cross-section in Fig. 7; in the cavity 147 is arranged a ring, such as shown in the plane view of Fig. 8. This ring is divided into two metal parts 149 and 150, each of which occupies slightly less than half its circumference and two intermediate insulating parts 151 and 152 designed to insulate the two conducting parts 149 and 150 from each other. In Fig. 7 one of the conducting parts 149 is shown in cross-section.

Let us suppose that the converter illustrated in Figs. 6-8 is used for supplying an apparatus with rectified current. In this case the secondary winding of the feed transformer has a median pole connected with one of the terminals of the apparatus. One of the two ends of the said secondary winding is connected with the brush 114, the other with the brush 116. The brush 115 is connected with the other terminal of the apparatus. The following connections inside the con-

verter are indicated diagrammatically by dotted lines:

The ring 111 is connected electrically with the pair of brushes 127; the ring 112 with the pair of brushes 128; and the ring 113 with the pair of brushes 129. The ring 123 is connected with the half ring 149; the ring 124 with the complete ring 148, and the ring 125 with the other half ring 150. The converter operates as follows:

When the pulley 110 revolves it communicates to the container 136 a rapid rotation round the axis of the shaft 121 and at the same time a motion due to the rotation of the said shaft 121 round the common fixed axis of the shafts 107 and 108. The first mentioned rotation strains the mercury in the annular chamber 145 to occupy constantly the periphery of the said chamber. The second motion, which is synchronous with the frequency of the network, causes the mass of mercury in the annular chamber 145 to move inside the said chamber at a speed synchronous with the frequency. Consequently, the said mass of mercury is constantly in contact with the metal ring 148 and alternatively in contact with the half rings 149 and 150. Therefore it forms an electric connection between the half ring 149, respectively 150, which it contacts, and the complete ring 148. Commutation takes place at the instant the mass of mercury reaches one of the insulating zones 151 or 152 between the half rings 149 and 150. The connections are established in such a way that the mercury always acts as cathode, the anode being alternately the solid metal parts 149 and 150. As in the first embodiment, commutation takes place in the arc formed between the mercury cathode and the solid metal anodes 149 and 150.

What I claim is:

1. A converter having at least one contact which opens and closes periodically and comprising a rotatable main shaft, at least one container having mercury therein, means mounting said container on said shaft for rotation about an axis which is eccentric relative to the axis of rotation of said main shaft and moves about the latter as said main shaft rotates, driving means for rotating said main shaft and for rotating said container about said eccentric axis so that the mercury in said container is centrifugally urged against the periphery of the container by the rotation of the latter about said eccentric axis and radially outwardly relative to the axis of said main shaft by the movement of said eccentric axis about the axis of the main shaft to thereby collect the mercury in at least one location in said container disposed radially outward relative to said axis of the main shaft, at least one solid electrode extending into said container and mounted for rotation with the latter about said eccentric axis to periodically extend into and be removed from the collected mercury, and an electrical circuit including the container, the mercury and the solid electrode arranged so that the mercury constitutes the cathode for the entire duration of each passage of current through the circuit with commutation taking place in the arc formed between said cathode and the electrode on opening of the circuit by withdrawal of the electrode from the collected mercury.

2. A converter as set forth in claim 1, wherein said eccentric axis is parallel to and spaced radially from the axis of said main shaft.

3. A converter as set forth in claim 1, wherein in said eccentric axis is arranged at right angles

to the axis of said main shaft and intersects the latter axis.

4. A converter as set forth in claim 1, wherein said solid electrode acts as the anode in said circuit during the whole passage of the current therethrough.

5. A converter as set forth in claim 1, wherein said solid electrode has a channel formed therein at the portion of the electrode which is last withdrawn from the collected mercury so that 10 said solid electrode acts as the anode in said circuit during the major part of each passage of current therethrough and mercury flows from said channel during the withdrawal of said electrode from the collected mercury to form the anode during the instant of commutation.

6. A converter as set forth in claim 1, wherein at least two circular conducting members are disposed concentric with said eccentric axis and mounted for rotation with said container about said eccentric axis, said circular conducting members being electrically connected to the mercury in said container and to said solid electrode, respectively, and fixed conducting tracks arranged with respect to said axis of the main shaft so that said circular conducting members effect continuous rolling contact with said tracks during movement of said container about said axis of the main shaft and said eccentric axis.

7. A converter as set forth in claim 6, wherein 30 said eccentric axis is parallel to and spaced radially from the axis of said main shaft to describe a cylindrical body of revolution during its movement about said main shaft, and said fixed conducting tracks are circular and concentric with said axis of the main shaft to receive said circular conducting members against the inner surfaces of the related tracks so that said circular conducting members are centrifugally urged against said tracks by the movement of 40 said container and said conducting members about said axis of the main shaft.

8. A converter as set forth in claim 7, wherein

said driving means is constructed and arranged to rotate said container and circular conducting members in the direction opposite to the rotation of said main shaft and at a speed providing a linear speed at the periphery of said circular conducting members equal to the linear speed of said periphery relative to said tracks resulting from the rotation of said main shaft so that said circular conducting members roll on said tracks without slipping.

9. A converter as set forth in claim 8, wherein said driving means includes epicyclic transmission means interposed between said main shaft and said container, said transmission means 15 having a relatively fixed member, and means for adjusting the position of said fixed member to adjust the angular position of said container and solid electrode around said eccentric axis without displacing said eccentric axis relative to said axis of the main shaft so that the timing of the commutation relative to the rotation of the main shaft may be varied.
